JOHN J. TATUM, OF BALTIMORE, MARYLAND

HOPPER CAR DOOR SECURING MECHANISM

Application filed August 20, 1929. Serial No. 387,242.

While I have, for the purposes of illustrating my invention, shown it embodied in a car with drop hopper doors designed to discharge under the car, it will, of course, be understood that my invention may be just efficiently used on cars, the drop doors of which discharge toward the sides of the car.

One of the objects of my invention is to provide for drop doors for railway cars a latch which functions to hold the door securely in closed position, and at the same time provide means to hold the side hopper sheets of the door from spreading should the sheet become torn from its fastening.

Another object of my invention is to provide a construction of keeper for the latch to prevent the latch from becoming unduly wedged in the same.

Another object of my invention is to provide a housing on the outside of the door for the latch; and with these and other objects in view my invention consists of the parts and combination of parts as will be hereinafter pointed out.

25 In the drawings:

Figure 1 is a side elevation of one end portion of a railway car showing my invention applied to the drop doors.

Figure 2 is an enlarged detail side elevation 30 of a portion of the car, and hopper, the door being shown in full lines in closed position and in dotted lines in open position.

Figure 3 is an enlarged detail elevation 35 looking at the outside face of the door.

Figure 4 is an enlarged detail transverse sectional view through the hopper and the door, the latch mechanism being in top plan view.

Figure 5 is an enlarged detail view of an 40 end of the keeper, the latch being shown in engagement therewith and in section.

The reference numeral 6 designates a railway car provided with the bottom hoppers 7 all of approved type. The doors 8 hinged at the top (as at 9) may be of any approved type and are preferably provided with rigidifying flange 10 to assist the door sheet in sustaining the load in the hopper, the bottom edge of the door being flanged as at 11, which flange extends under the hopper as

clearly shown in Figure 2. The side sheets, or walls of the hopper at their bottom edge portions may, if preferred for the sake of rigidity and reinforcement, be provided on their outer faces with pressed angle iron plate 55 12 secured by rivets 13, or other devices, said angle iron, preferably extending across the bottom of the hopper at the discharge end.

According to my invention I secure by rivets, or otherwise, to the side sheets, or side 60 sheets and angle irons 12, a keeper plate 14 which, in case of angle irons being used, is deflected as at 15 to give clearance for the flange 16 of the angle iron and the flange 10 at the side edge of the door 8, as clearly shown 65 in Figure 4. The outer end of the keeper plate is notched, one wall 18 of the notch being inclined toward the hopper, while the bottom wall 19 is preferably flat. The wall 20 of the notch is undercut, as shown in Figure 5. This wall 20 constitutes the outer 70 bearing for the latch and the undercut feature permits the latch to be forced by the load on the door and the weight of the door into snug engagement therewith and held 75 against accidental disengagement whereby the latch is automatically held in locked position. Preferably, the bottom of the latch, in locked position is spaced from contact with the bottom wall 19 of the notch in the 80 keeper to prevent the latch becoming wedged in the notch when it is forced against the undercut wall 20 of the notch. With this construction the bottom corner of the latch cannot bite into the face of the wall 19 of the 85 notch, besides which this feature prevents any strain from being thrown upon the hinge pin by the lifting of the door by the force of the dog upon the latch.

Preferably the doors 8 are provided with 90 spreader bars, or stiffeners 21, which may be of any desired commercial shape. I secure to the stiffener 21 a housing 22 at the outer end of which are upstanding flanges 23. In the housing I mount the latch 24 on a pivot 95 25, said latch extending at its free end beyond the side edge of the door and beyond the keeper plate 14 (as clearly shown in Figures 3 and 4), the extreme outer end portion of the latch being bent backward and de- 100

flected slightly downward, this bent end 26, as shown in Figures 2 and 4 extending lengthwise outside of the keeper plate. This end 26 by reason of its position relative to the keeper plate functions to keep the side plates or sheet of the hopper from spreading should it become torn from its fastenings, and the end 26 further provides means which may be struck by a suitable instrument to throw the latch from an engaged position with the keeper. The end of the keeper is tapered as at 27 to engage the latch when the door is forced to closed position so that it can be readily moved to the notch in the keeper to hold the door in closed position.

The latch is loosely pivoted in the housing so as to permit it to slightly tilt or rock on its pivot to fit snugly against the undercut wall 20 of the notch in the keeper. The lower 20 side edge of the door in line with the locking devices is without a flange so as to permit free movement of the door without interfering with either the hook or the latch.

Between the upstanding flanges 23 of the 25 housing 22 I pivot a weighted lock 28 pivoted off balance which is adapted to move by reason of its off balance to wedging locking engagement against the upper edge of the latch and provide an additional means holding the 30 latch against accidental disengagement with its keeper.

As will be seen from Figure 5 the clearance is maintained between the bottom edge of the latch 24 and the bottom wall 19 of the 35 notch in the keeper 14 so that when the door is in its closed position the pressure on the latch exerted will not result in binding action on the hinge pin of the door.

As shown in the drawings the side flange 40 10 of the door is notched or cut away as at 30 to give free clearance for the door latch 24.

The latch 24 is rounded or bevelled as at 31 on its top and bottom inner edges as shown in Figure 5, the purpose of which is to permit 45 the latch to move easily on the inclined edge 27, and by having both of these corners rounded the latch may be used as a right or left hand latch.

The extension 26 at the free end of the 50 latch may be extended forwardly.

What I claim is:

1. In a hopper car, a hopper, a hopper door, a keeper at the side of the hopper having a notch provided with a substantially 55 straight bottom wall, an inner wall inclined inwardly and upwardly toward the door and an outer wall which is undercut, and a latch mounted on the door for swinging movement parallel with the door into and out of engagement with the notch and for rocking movement at right angles to its plane of swinging movement to underlappingly engage the undercut outer wall of the notch.

2. In a hopper car, a hopper, a hopper 60 door, a keeper at the side of the hopper hav-

ing a notch provided with a substantially straight bottom wall, an inner wall inclined inwardly and upwardly toward the door and an outer wall which is undercut, and a latch mounted on the door for swinging movement parallel with the door into and out of engagement with the notch and for rocking movement at right angles to its plane of swinging movement to underlappingly engage the undercut outer wall of the notch, the arrangement being such that in its locking position the latch lies spaced from engagement with the bottom wall of the notch.

3. In a hopper car, a hopper, a hopper door, a keeper at the side of the hopper having a notch provided with a substantially straight bottom wall, an inner wall inclined inwardly and upwardly toward the door and an outer wall which is undercut, and a latch mounted on the door for swinging movement parallel with the door into and out of engagement with the notch and for rocking movement at right angles to its plane of swinging movement to underlappingly engage the undercut outer wall of the notch, said latch having a rounded bottom face for sliding engagement with the keeper and having a limit of locking movement such that the latch when in locking position lies above and out of engagement with the bottom wall of the keeper notch.

4. In a hopper car, a hopper, a hopper door, a keeper at the side of the hopper provided with a keeper notch having a substantially straight bottom wall, an undercut outer wall and an upwardly and inwardly inclined inner wall, and a latch bar mounted on the door for swinging movement parallel with said door into and out of engagement with the keeper and for rocking movement at right angles to the plane of the door to underlappingly engage the undercut wall of the notch, the latch having a limit of locking movement such that the latch when in locking position lies above and out of contact with the bottom wall of the notch.

5. In a hopper car, a hopper, a hopper door, a keeper at the side of the hopper provided with a keeper notch having a substantially straight bottom wall, an undercut outer wall and an upwardly and inwardly inclined inner wall, a latch bar mounted on the door for swinging movement parallel with the door into and out of engagement with the keeper and for rocking movement at right angles to its plane of pivotal movement to underlappingly engage the undercut wall of the notch, the latch having a limit of locking movement such that the latch when in locking position lies above and out of contact with the bottom wall of the notch, and a right angular extension at the free end of the latch adapted to extend across the notch beyond the latch and to engage the outer

surface of the latter to prevent the hopper side from spreading.

6. In a hopper car, a hopper, a hopper door, a keeper at the side of the hopper having a notch provided with a substantially straight bottom wall, an inner wall inclined inwardly and upwardly toward the door and an outer wall which is undercut, and a latch pivoted to swing in a vertical plane parallel with the door for movement into and out of engagement with the keeper notch and loosely mounted on its pivot for rocking movement under outward pressure from the door in a plane at right angles to its swinging movement to underlappingly engage the undercut outer wall of the notch.

7. In a hopper car, a hopper, a hopper door, a keeper at the side of the hopper having a notch provided with a substantially straight bottom wall, an inner wall inclined inwardly and upwardly toward the door and an outer wall which is undercut, and a latch pivoted to swing in a vertical plane parallel with the door for movement into and out of engagement with the keeper notch and loosely mounted on its pivot for rocking movement under outward pressure from the door in a plane at right angles to its swinging movement to underlappingly engage the undercut outer wall of the notch, said latch being of a depth slightly less than the depth of the notch and being limited in its swinging movement so as to be spaced from the bottom wall when in latching position, said latch having rounded upper and lower edges.

In testimony whereof I affix my signature.
JOHN J. TATUM.
